DESIGN FOR A GAUGE PLATE FOR SLICING MACHINES

Arthur H. Ahrndt, La Porte, Ind., assignor to
U. S. Slicing Machine Company, La Porte, Ind.,
a corporation of Indiana

Application March 24, 1945, Serial No. 118,680

Term of patent 14 years

(Cl. D55—1)

To all whom it may concern:

Be it known that I, Arthur H. Ahrndt, a citizen of the United States, residing at La Porte, in the county of La Porte and State of Indiana, have invented a new, original, and ornamental Design for Gauge Plate for Slicing Machines, of which the following is a specification, reference being had to the accompanying drawing, forming a part thereof.

Fig. 1 is a front elevational view of a gauge plate for slicing machines showing my new design;

Fig. 2 is a rear elevational view thereof;
Fig. 3 is an elevational view of the left end of
Fig. 1; and

Fig. 4 is a sectional view on the line 4—4 of
Fig. 1.

I claim:

The ornamental design for a gauge plate for
slicing machines, as shown.

ARTHUR H. AHRNDT.
